COIN-CONTROLLED UNIT FOR SLOT MACHINES

Clarence M. Frost, Milton, Mass., assignor to Frost Vending Machine Co., Milton, Mass., a corporation of Massachusetts

Application February 3, 1947, Serial No. 726,055

2 Claims. (Cl. 194—97)

1

The present invention relates to coin-controlled units for a slot machine and is more particularly concerned with devices for accepting good coins and rejecting slugs.

The object of the present invention is to provide a coin-controlled device which is sensitive to size and weight within tolerable limits, and is also capable of discriminating between a milled and a smooth edge. A subsidiary object is to provide an improved magnetic arrangement for rejection of slugs of magnetic material.

With these objects in view the present invention comprises the coin-controlled unit herein-after described and particularly defined in the claims.

In the accompanying drawings, Fig. 1 is a side view of the preferred unit according to the present invention; Fig. 2 is a view of the opposite side; Fig. 3 is a view similar to Fig. 1 but with the side plate removed to show the interior arrangement of the parts; Fig. 4 is a section of line 4—4 of Fig. 1; Fig. 5 is a section of line 5—5 of Fig. 3; Figs. 6—11 are diagrams illustrating the operation of the device upon introduction of a good coin; Figs. 12 and 13 illustrate the rejection of a slug; Fig. 14 is a sectional detail view taken on line 14—14 of Fig. 3; Fig. 15 is a section of line 15—15 of Fig. 3 showing the magnet arrangement and Fig. 16 is a detailed plan view of the parts shown in Fig. 15.

The illustrated embodiment of the invention comprises two side plates 20 and 22 separated by a distance somewhat greater than the thickness of a coin to be handled. The spacing is determined by the thickness of certain coin chutes to be presently described.

As shown in Fig. 3 the unit is provided at the top with a coin direction chute 24 having a curved surface into which a coin is introduced. The end of the chute 24 terminates adjacent to a window 26 which is cut in the side plate 22 for purposes of rejection of magnetic slugs as will be hereinafter described. As shown in Fig. 5 the chute 24 is beveled slightly so that a coin is normally held against the side plate 20 in order that a good coin will have no tendency to be deflected through the window 26.

The coin, after following the chute 24, falls on a pivoted chute 28. The chute is pivoted at 30 in a sensitive low friction bearing 32 as indicated in Fig. 4. The chute 28 has a concave surface 34 and at its free end is provided with a rod 36 which extends outwardly through an opening 38 in the side plate 20. On the rod 36 is provided a weight 40. The end of the pivoted

chute 28 rests on a shoulder 42 formed in a spacing plate 44. The left hand end of the chute as viewed in Fig. 3 faces a plate 46, the surface of which forms a continuation of the chute 28. The corner 47 of the plate 46 is important as will be explained later. This upper surface of the plate 46 leads to a rejection or by-pass opening 48.

It will be observed that a shoulder 50 is provided in the under surface of the initial chute 24. This shoulder provides a corner serving as a stop for a coin.

A stationary chute 52 extends from left to right below the chute 28 to receive an acceptable coin from 28 and to discharge it onto a pivoted chute 54 which is similar in form to the chute 28. The chute 54 is pivoted at 56 and is provided with a weight 58 which normally holds the right hand end of the chute against a shoulder 60 on the plate 44. The weight 58 is mounted on a rod 62 which extends through a suitable opening in the side plate 20. A similar opening 64 is formed in the opposite side plate 22. Through this latter opening extends a rod or bar 66, the end of which engages a part of the chute 54. When the chute is tilted by a coin, the bar 66 is free to move to the left as indicated in Fig. 14.

Opposite the end of the chute 54 is a stop pin 68 against which the coin is ultimately stopped. As shown in Fig. 14, the pin 68 is mounted in a bracket 70 and is urged by a spring 72 away from its stop position. The pin is held in the stop position against the action of the spring by a suitable member indicated at 74, arranged so that, upon operation of the delivery mechanism, the pin will be retracted to permit the coin to drop into a suitable receptacle.

The operation of the unit, as thus far described, is illustrated by Figs. 6 to 11. These figures illustrate the operation of the device upon the passage of a good coin.

As shown in Fig. 6, a coin, which may be a quarter dollar, is introduced into the slot between the plates 20 and 22 immediately above the chute 24. As it drops off the right hand end of the chute 24, it falls on the right hand end of the chute 28. From there it passes, as indicated in Fig. 7, until it is momentarily stopped by the shoulder 50 on the under side of the plate 24, as indicated at A in Fig. 7. From the point A the further course of the coin depends on whether it is a good coin or a bad one. In the case of a good coin, particularly if it has a milled edge, it will pass successively through the posi-

tions indicated in Figs. 8 to 10, whereas if it is a bad coin, it will be rejected through the window 48 as indicated in Figs. 12 and 13. The action of the mechanism in discriminating between a good and a bad coin is rather complicated. To facilitate the description of these operations, attention is first directed to the balance of the pivoted chute 28.

The chute is so counterweighted by the weight 40 that a coin of approximately normal size and weight has a balance point near the position A of Fig. 7. For convenience, the balance point is indicated by position W for a coin of full size and normal weight. This means that a coin of such size and weight in the position W will statically balance the weight 40. It will be noted that position W is only slightly in back of the stop position A. For a coin of less weight, the balance position would be nearer the point A. It is contemplated, however, that a coin or slug of the lightest weight which the machine would be expected to receive, would have a balance point in back of position A; in other words, any coin or slug which the machine would receive, would still be capable of statically overbalancing the weight 40.

A coin of full size and weight will strike the shoulder 50 and be stopped momentarily in position A. Since this is beyond the balance point W, the chute 28 will tilt. In Fig. 8 the chute is shown in partially tilted position. During the tilt the coin has moved to position B. The former "stop" position on the chute is indicated by the letter A. It will be seen that, between the conditions of Figs. 7 and 8, the coin has rolled down the chute from former position A to position B. Furthermore, the coin has moved downwardly and the chute has swung about its pivot. In swinging about the pivot the moment of inertia of the chute has to be taken into account. The weight 40 must have accelerated sufficiently to carry the chute into the position of Fig. 8, while the coin has rolled down the chute from its position of rest at A to its new position B. If the chute has swung far enough, as is the case shown in Fig. 8, the left hand end of the chute will have been depressed sufficiently so that the coin will not roll over the corner 47. This is the case of a good coin which is accepted by the mechanism.

From the position of Fig. 8, since the chute is overbalanced, the coin drops through and falls on the stationary chute 52. It rolls down the chute 52 and drops on the chute 54, finally completing its motion against the stop pin 68 as indicated in Fig. 10. At this time the chute 54 is tilted but the coin is held against the stop.

As a result of the tilting of the chute, the release bar 63 is now free. As shown in Fig. 14, this bar may now be pushed to the left, thereby operating the delivery mechanism. The delivery mechanism is not described in detail herein but it may take any suitable form. As shown in Fig. 14, a manually operated plunger 76 is provided. This plunger has a portion engaging an inclined surface 78 on the release bar. Thus, upon tilting of the chute 54 into position at Fig. 10, the plunger 76 may be pushed inwardly. The side-wise motion of the bar 66 may be utilized to deliver the vended goods.

The same motion of the plunger may be utilized to release the coin so that it may drop into a suitable receptacle. Thus, as shown in Fig. 14, the plunger has an extension 80 which is arranged to hold the pin in "stop" position. When the plunger is pushed in, the pin 68 is retracted by the spring 72. The coin then falls off the

chute into a suitable receptacle as indicated in Fig. 11.

It will be understood that a certain tolerance for both size and weight is necessary. If a coin is too small to be stopped by the shoulder 50, it will of course pass directly to the rejection opening without causing any appreciable tilt of the chute 28. A coin may, however, be stopped by the shoulder 50 and still be too small to be accepted by the mechanism. In such a case, its stop position A is too far to the left and upon slight depression of the chute 28, the coin is free to roll and therefore, rolls over the corner 47 before the inertia of the weight 40 has been sufficiently overcome to depress the chute into the position of Fig. 8. A coin of the right diameter but too light has a balance point to the left of the position W of Fig. 7. Hence, the stop position A is so close to the balance position, that the weight 40 is not quickly overbalanced. The chute depresses relatively slowly and the coin has time to ride over the corner 47 before the chute has been depressed to such a position as is indicated in Fig. 8.

It has been stated heretofore that the present invention has the effect of discriminating between a good coin and a bad coin by detection of the milled edge. It will be seen from Figs. 7 and 8 that the corner 59 tends to engage in a notch of the milled edge of the coin. Because of that and also because of the frictional engagement of the milled edge against the surface of the chute 28, the coin is actually stopped in the position of Fig. 7 and the above-described actions take place from that point. In the case of a smooth edged coin, however, the coin tends to bounce back from the shoulder 50. This is indicated in Fig. 12. Thus, the coin first strikes the shoulder at position A and bounces back slightly to position F. While the amount of bounce may be slight, position F is nevertheless quite close to the balance point W. At F the coin may be considered to have no momentum; in other words, the stop position of the coin is at F rather than at A. At F the coin is so near the balance point that it is capable of accelerating the chute 28 only at a very slow rate. Hence, as shown in Fig. 13, when the coin reaches the shoulder 47, the chute has been only slightly depressed and the coin is able to roll over the corner 47 and be discharged through the by-pass. It will be observed that a slight depression of the chute 28 is necessary to allow the coin to pass the corner 47, but full passage for the coin is provided at the corner 47 and beyond.

The action of discriminating between a smooth and a milled edge is quite sensitive and the device will accept a coin in which only a slight milling is left, even though such coin has been reduced in size and weight by normal wear. However, by the action herein described, the present invention makes use of the milling to effect a greater discrimination than can be accomplished by size and weight alone, and thus diminishes the losses due to bad coins.

In addition to effecting discrimination for size, weight and smoothness, the invention provides simple and effective means for rejecting slugs of magnetic material. While such slugs might be rejected because of weight or smoothness, the magnetic rejection diminishes the possibility of receiving a bad coin. As shown in Figs. 3, 15 and 16, a permanent magnet 82 is mounted on a bracket 84 attached to a fixed part 75 of the machine. The magnet is disposed in an

inclined position above the window 26 so that its field can act on a coin rolling down the chute 24. The forces acting on an iron or steel slug are both upward and outward. The upward force tends to lift the coin off the beveled surface of the chute 24, and the outward force tends to pull the slug toward the right, as viewed in Figs. 15 and 16. Accordingly the slug is deflected out through the window 26, from which it falls into any suitable receptacle. Owing to the speed of the coin as it passes under the magnet, the slug is not attracted into actual contact with the magnet, and hence it has no opportunity to block the machine or to weaken the force of the magnet.

It will be seen that the present invention provides for effective discrimination between good and bad coins, while still affording adequate tolerance for partially worn coins. The device is simple and inexpensive to manufacture and is capable of easy adjustment.

Having thus described the invention, I claim:

1. A coin-controlled unit comprising a pivoted and counterweighted chute down which a coin rolls, stopping means above the chute to engage the upper portion of a coin and to effect momentary arresting of a milled coin but to cause a smooth coin to bounce back, the chute having a static balance point for a coin slightly in back of the stopping means, whereby the rate of tilt of the chute depends on the relation of the stopping point of a coin to said static balance point, and a member having a corner opposed to the end of the chute, said corner sep-

arating acceptance and rejection passages, the corner being in advance of the said stopping means.

5 2. A coin-controlled unit comprising a pivoted and counterweighted chute down which a coin rolls, shoulder above the chute to engage the upper portion of a coin and to effect momentary arresting of a milled coin but to cause a smooth coin to bounce back, the chute having a static balance point for a coin slightly in back of the shoulder, whereby the rate of tilt of the chute depends on the relation of the stopping point of a coin to said static balance point, and a member having a corner opposed to the end 10 15 of the chute, said corner separating acceptance and rejection passages, the corner being in advance of the said shoulder.

CLARENCE M. FROST.
